UNITED STATES PATENT OFFICE.

WALTER M. AUSTIN, OF SWISSVALE, PENNSYLVANIA, ASSIGNOR TO WESTINGHOUSE ELECTRIC & MANUFACTURING COMPANY, A CORPORATION OF PENNSYLVANIA.

TRIPPING DEVICE.

1,408,243.

Specification of Letters Patent. Patented Feb. 28, 1922.

Application filed June 19, 1918. Serial No. 240,852.

To all whom it may concern:

Be it known that I, WALTER M. AUSTIN, a citizen of the United States, and a resident of Swissvale, in the county of Allegheny and State of Pennsylvania, have invented a new and useful Improvement in Tripping Devices, of which the following is a specification.

My invention relates to tripping devices and particularly to overload and reverse-current tripping devices for circuit interrupters.

One object of my invention is to provide an overload and reverse-current tripping device that shall have only a single voltage and a single current operating coil.

Another object of my invention is to provide a magnetizable member for a tripping device, of the above indicated character, that shall be of such shape as to co-operate with a polarized armature to positively actuate the armature in two directions in accordance with the direction of flow of current through the interrupter.

Another object of my invention is to provide a magnetizable member, of the above indicated character, that shall actuate a second armature under predetermined overload conditions.

A further object of my invention is to provide a device of the above indicated character that shall be inexpensive to construct, applicable to existing types of circuit interrupters and effective in its operation.

In practicing my invention, I provide a current and a voltage coil that are operatively connected to the circuit interrupter. An armature is loosely mounted in the voltage coil. A magnetizable member is inductively connected to the current coil and has two arms that are of such shape as to constitute poles at the respective ends of the armature, on opposite sides thereof. A second armature is adapted to co-operate with the poles on the under side of the first-mentioned armature and is so adjusted that it will be attracted under predetermined overload conditions. The first mentioned armature is polarized by the voltage coil and is thus maintained positively in one position, under normal conditions, and is positively attracted in the opposite direction to another position when the current traversing the voltage coil reverses.

In the accompanying drawings, Fig. 1 is a side view, partially in section and partially in elevation, of a circuit interrupter embodying my invention; Fig. 2 is a front view, partially in section and partially in elevation, of the circuit interrupter shown in Fig. 1, Fig. 3 is a fragmentary side elevational view of a modified form of tripping device embodying my invention.

Fig. 4 is a detail view of the magnetizable members and their co-operating armatures, in assembled relation;

Fig. 5 is a detail view of a portion of one of the magnetizable members, and

Fig. 6 is a view looking from the top of Fig. 5.

A circuit interrupter 1 is mounted on a panel board 2 and comprises, in general, two stationary main contact members 3 and 4, a main bridging contact member 5, a supporting arm 6 therefor, an operating lever arm 7 and a latching device 8.

A current coil 9 is disposed between the brackets 10 upon which the operating lever arm 7 is mounted and is so connected to the stationary contact member 4 and a stud 11 as to be traversed by the current traversing the interrupter 1. The coil 9 is disposed around a core member 12 to the ends of which are connected magnetizable members 13 and 14. The magnetizable member 13 is of such shape that it constitutes a pole 15 at one end of a voltage coil 16 and extends behind the voltage coil 16 and to the opposite end thereof to form a second pole 17. Similarly, the magnetizable member 14 constitutes a pole 18 at one end of the coil 16 and extends in front of the coil 16 to the opposite end thereof and constitutes a pole 19 adjacent the pole 15.

A magnetizable armature 20 is loosely disposed in the opening in the voltage coil 16 between the poles 15 and 19 and 18 and 17, respectively, and is supported by a lever arm 21 that is pivotally mounted on bracket 22 on the portion 23 of the magnetizable member 14. The member 21 is provided with a counter-weight member 24 that is adapted to be moved by a screw-threaded member 25 to any position therealong for the purpose of calibrating the device. The counter-weight member 24 co-operates with a scale 26 to indicate the setting of the device.

The poles 17 and 19 of the members 13 and 14

- and 14, respectively, extend downwardly to constitute poles 27 and 28 that are adapted to attract an armature 29, under predetermined conditions. The armature 29 is mounted on a lever arm 30 that is pivotally mounted on a bracket 31 and is provided with a counter-weight 32 that is adapted to be adjusted by a screw-threaded member 33 with respect to a scale 34. The stationary member 35 of a dash-pot 36 is supported on a projection 37, and the movable member 38 of the dash-pot is operatively connected to the lever arm 30. If it is not desired to retard the time of operation of the armature 29, the dash-pot 36 may be omitted and a stop member 39, substantially as shown in Fig. 3 of the drawings, may be provided for limiting the downward movement of the armature 29.
20. The latching device 8 comprises a projection 40 on the operating lever arm 7 and a latching member 41, that is pivotally mounted on the pin 42 in the brackets 10. A rod 43 extends from a position adjacent one arm 44 of the latch 41 to a position 46 adjacent the arm 30, and a rod 45 extends to a point adjacent the arm 21. Thus, when the armatures 20 and 29 are actuated either by a reversal of current traversing the circuit interrupter or by an overload therein, the latch 41 will be moved in a clockwise direction to thus release the projection 40 and permit the circuit interrupter 1 to be tripped.
35. The essential feature of my invention is that the magnetizable members 13 and 14 severally constitute poles at the ends of the voltage coil 16 adjacent opposite sides of the armature 20 and terminate in poles 27 and 28 that co-operate with an overload armature 29. The armature 20 is polarized by the voltage coil 16 and thus, if the voltage coil 16 is properly connected, the armature will co-operate with the poles 17 and 19 to be positively held in its lowermost position, under normal conditions of operation. When the current traversing the circuit interrupter 1 reverses, the polarity of the poles 15, 17, 18 and 19 will reverse and thus the armature 20 will be positively actuated to its uppermost position to thereby actuate the rod 43 to trip the interrupter. By so forming the members 13 and 14, the armature is positively actuated 50 to its proper position in accordance with the direction of flow of current through the interrupter. When the current traversing the interrupter exceeds a predetermined value, the poles 27 and 28 will attract the armature 29 to thereby, after a lapse of time that is dependent upon the setting of the dash-pot 36, actuate the rod 45 to trip the interrupter.
60. My invention is not limited to the specific device illustrated as it may be variously

modified without departing from the spirit and scope of the invention as set forth in the appended claims.

I claim as my invention:

1. A reverse-current tripping device for 70 a circuit interrupter comprising a current coil, a voltage coil, two magnetizable members inductively related to the current coil, and a laterally movable armature disposed in the voltage coil, said magnetizable members 75 severally comprising two poles one above the armature at one end of the voltage coil and one below the armature at the other end of the voltage coil.

2. A reverse-current tripping device for 80 a circuit interrupter comprising a current coil, a voltage coil, two magnetizable members operatively connected to the current coil, and a polarized armature disposed in the voltage coil, said magnetizable members 85 severally being so shaped that they constitute two poles, one above the armature at one end of the voltage coil and one below the armature at the other end of the voltage coil.

3. A reverse-current tripping device for 90 a circuit interrupter comprising a current coil, a voltage coil, two magnetizable members operatively connected to the current coil, and a polarized armature disposed in 95 the voltage coil, said magnetizable members severally being so shaped that they constitute two like poles, one below and one above the armature at opposite ends of the voltage coil.

4. An overload and reverse-current tripping device for a circuit interrupter comprising a current coil, a voltage coil, two magnetizable members inductively related to the current coil, a movable armature disposed in the voltage coil, and a second movable armature, said magnetizable members severally being so shaped that they form two poles one above and one below the first armature at opposite ends of the voltage coil, said second armature being adapted to co-operate with the poles below the first armature only.

5. A tripping device for a circuit interrupter comprising a current coil, a voltage 115 coil, two magnetizable members, an armature disposed in the voltage coil, and a second armature adapted to be attracted by the magnetizable members when a predetermined current traverses the current coil, said magnetizable members being so positioned with respect to the first armature that it is positively attracted in one direction normally and is positively attracted in another direction when the current traversing the current coil reverses.

6. A tripping device for a circuit interrupter comprising a current coil, a voltage coil, a magnetizable member inductively associated with the current coil, and an arma- 125

130

- ture inductively associated with the voltage coil, said magnetizable member being of such shape that it forms a pair of unlike poles adjacent each end of the armature.
5. 7. A tripping device for a circuit interrupter comprising a current coil, a voltage coil, a magnetizable member inductively associated with the current coil, and an armature inductively associated with the voltage coil, said magnetizable member being of such shape that it co-operates with the armature to hold the armature in one position under normal conditions and in another position when the current traversing the current coil reverses.
8. A tripping device for a circuit interrupter comprising a magnetizable member having two arms, means for inducing magnetic lines of force therein in accordance with the current traversing the interrupter, a voltage coil, and a pivotally mounted armature inductively associated with the voltage coil, said arms of the magnetizable member being of such shape as to severally form a pole adjacent each end on opposite sides of the armature.
9. A tripping device for a circuit interrupter comprising a magnetizable member having two arms, means for inducing magnetic lines of force therein in accordance with the current traversing the interrupter, a voltage coil, a pivotally mounted armature inductively associated with the voltage coil, and a second armature, said arms of the magnetizable member being of such shape as to severally form a pole adjacent each end on opposite sides of the first armature,
- said second armature being adapted to co-operate with one pole adjacent each end of the first armature.
10. A tripping device for a circuit interrupter comprising a single voltage coil, a single current coil and means responsive to currents in said coils for tripping the interrupter in response to a change in value, and upon a reversal, of current in the interrupter, the said coils being operatively unrelated.
11. A tripping device for a circuit interrupter comprising two coils only and means responsive to current in the coils for tripping the interrupter in response to a change in value, and upon a reversal of current in the interrupter, the said coils being operatively unrelated.
12. The combination with two electromagnets only and an armature for each of the same, of means for so polarizing one of said magnets as to attract one of said armatures in response to currents therethrough in either direction, the other magnet being responsive to changes in the current therethrough to attract the other armature.
13. A tripping device for circuit interrupters comprising a single voltage coil, a single current coil, an armature for each of said coils and pole members related to both of said coils to attract the said armatures upon a change in value or direction of the current in the interrupter.

In testimony whereof, I have hereunto subscribed my name this 29th day of May, 1918.

WALTER M. AUSTIN.
